CORE REMOVING PLUNGER

John H. Howard, Huntington Park, Calif., assignor to Globe Oil Tools Company, Los Nietos, Calif., a corporation of California

Application June 12, 1934, Serial No. 730,212

3 Claims. (CL 255—1)

This invention relates to apparatus for use in connection with a well core drill, or the like, and relates more particularly to a plunger for forcing or removing a core from the barrel of a well 5 core drill. A general object of this invention is to provide a simple, practical and particularly effective plunger useful in removing a core of earth formation from the barrel of a core drill.

The cores received in the barrels of well core 10 drills are often quite difficult to extract or remove. It is the common practice to arrange a plunger in the barrel above or at one end of the core and then pass fluid under pressure into the barrel behind the plunger to drive the plunger 15 through the barrel and thus force the core from the barrel. Because of the irregularities usually present on the interior of a core drill it is not practical to employ a plunger having metallic parts for sealing with the interior of the barrel 20 and the plungers now in general use are formed of rubber and the like. When a core is relatively loose in the barrel a pipe or similar object is sometimes employed to drive the plunger through the barrel for the purpose of forcing the core 25 from the barrel. This use of a pipe or the like to force the plunger and core through the barrel is very destructive to a rubber plunger or a plunger having exposed sealing parts that may be injured by the pipe.

30 An object of the invention is to provide a plunger for use in removing a core from a barrel that includes means for sealing with the interior of the barrel that are fully protected against engagement by a pipe, rod or similar object that 35 may be employed to drive the plunger through the barrel.

Another object of the invention is to provide 40 a core removing plunger that includes a novel and particularly effective scraping or wiping element for clearing sand and other solid material from the inner wall of the barrel in advance of the sealing parts so that such solid matter may not pass or catch in the sealing parts to allow the leakage of fluid under pressure past the 45 plunger.

Another object of the invention is to provide a 50 plunger of the character mentioned that includes spaced cup leathers or sealing cup parts arranged and formed to be particularly effective in sealing with the interior of the core barrel.

Another object of the invention is to provide a 55 core removing plunger of the character mentioned in which the sealing parts and the scraping or wiping element are readily replaceable.

A further object of the invention is to provide

a plunger of the character mentioned that is simple and inexpensive of manufacture and that is sturdy and long wearing.

Other objects and features of my invention will be better and more fully understood from the 5 following detailed description of a typical form and application of the invention, throughout which description reference may be had to the accompanying drawing, in which:

Fig. 1 is a one quarter longitudinal cross section 10 view of a core barrel containing a core illustrating the plunger provided by the present invention in the barrel and means supplying fluid pressure to the barrel to drive the plunger and core through the barrel. Fig. 2 is an enlarged 15 side elevation of the plunger illustrating one quarter in longitudinal cross section. Fig. 3 is an elevation of the rear or trailing end of the plunger and Fig. 4 is a transverse detailed sectional view taken as indicated by line 4—4 on 20 Fig. 2.

The plunger of the present invention is adapted to be employed in removing cores from the barrels of various classes of tools and may be used in connection with various forms of apparatus for 25 passing fluid under pressure into the barrel. In the drawing I have shown the improved plunger employed in removing a core C from a more or less typical barrel B and have shown fluid pressure being supplied to the barrel by a pump P 30 whose delivery line L is connected with the barrel B by the pressure head H. The head H is removably connected with the barrel B and operates to pass the pumped fluid into the barrel and seals the end of the barrel to retain high 35 fluid pressures therein. The present invention is not primarily concerned with the particular type of pump or pressure head used in removing the core from the barrel and the invention is not to be construed as limited or restricted to the 40 specific application of the invention illustrated in the drawing, but is to be taken as including any features or modifications that may fall within the scope of the claims.

The core extracting or removing plunger provided by the present invention, includes, generally, a body 10, a wiping element 11 on the forward end of the body for scraping or removing solid matter from the internal wall of the barrel B, and means 12 in trailing relation to the element 11 for sealing with the interior of the barrel B.

The body 10 is formed of steel, iron or other suitable metal and is substantially cylindrical in its general configuration. The body 10 is pro- 55

portioned to enter and pass through the barrel B with suitable clearance. In the preferred construction the body 10 is hollow and is closed at one end. A wall or head 13 closes the forward end of the body. Internal reinforcing ribs 14 extend along the inner wall of the body 10 and join at a ring 15 on the inner side of the head 13. The inner or forward portion of the body 10 is stepped at its periphery having a portion 16 of reduced external diameter. A projection or extension 17 is provided on the outer side of the head 13. The extension 17 is hollow or tubular and is concentric with the longitudinal axis of the plunger. An annular inwardly projecting flange 18 is provided on the rear end of the body 10 to carry a projection or extension 19. The extension 19 is concentric with the longitudinal axis of the body and in the case illustrated in the drawing is of the same diameter as the forward extension 17. The extension 19 is preferably tubular having an opening 20 whereby the body 10 is open at its rear end. The body 10 just described may be one piece, or integral.

The wiping element 11 is a feature of the invention and operates to scrape or clear the internal wall of the barrel B of solid matter and thus provide for the proper efficient operation of the sealing means 12. The element 11 is carried on the forward body extension 17 and is in the nature of an annular body of rubber, rubber composition or the like. In the preferred form of the invention the wiping element 11 is comparatively thick and rests or bears inwardly on the extension 17. The element 11 fits the barrel B snugly or very closely to scrape sand and loose solid matter from the interior of the barrel as the plunger is forced through it. A ring or nut 21 is threaded on the extension 17 and retains the wiping element 11 in position, operating to clamp it against the head 13 through the medium of one of the sealing parts of the means 12. The wiping element 11 is normally larger in diameter than the body 10 and may have a plane cylindrical periphery as illustrated throughout the drawing.

The means 12 operates to effectively seal with the interior of the barrel B whereby a high pressure may be built up behind the plunger to force the plunger through the barrel and thus remove or drive the core C from the barrel. The means 12 includes a front or forward sealing part 25 and a rear sealing part 26. The sealing parts 25 and 26 are in the nature of sealing cups or cup leathers and may be formed of leather, rubber or the like. The forward sealing part 25 has its inwardly projecting flange 27 clamped between the wiping element 11 and the forward face of the head 13. The outer or peripheral flange 28 of the forward sealing part 25 projects rearwardly around the portion 16 whose reduced diameter 60 leaves an annular space for receiving the flange.

The rear or trailing sealing part 26 surrounds the body extension 19 and its inwardly projecting flange 30 is clamped against the body flange 18 by a nut 31. The nut 31 is threaded on the extension 19 and is of less diameter than the body 10 to leave a peripheral annular space to receive the sealing flange 32 of the part 26. The nut 31 projects rearwardly beyond the rear edge of the sealing part 26 and its rear or outer end 70 33 protects the sealing part against engagement by a pipe or rod that may be employed to drive or force the plunger through the barrel B. The rear edges of the sealing flanges 28 and 32 may be bevelled away in the usual manner to admit fluid under pressure behind the flanges to force

them outwardly against the internal wall of the barrel B. Fluid under pressure at the rear of the plunger holds the sealing flanges 28 and 32 outwardly against the interior wall of the barrel B so that the sealing parts 25 and 26 prevent the fluid pressure from passing around the plunger and provide for the building up of high fluid pressure behind the plunger.

It is believed that the operation of the plunger provided by the invention will be readily understood from the foregoing detailed description. To remove the core C from the barrel B the plunger is inserted in the barrel behind the core and the pressure head H is then connected to the barrel so that fluid under pressure from the pump P is passed into the barrel behind the plunger. Fluid under pressure at the back of the plunger of course drives or forces the plunger through the barrel and the plunger in turn pushes the core from the barrel. During the advance or movement of the plunger through the barrel the element 11 has wiping or scraping engagement with the interior of the barrel to remove sand and loose solid matter therefrom. The sealing flanges 28 and 32 of the sealing parts 25 are tightly forced against the interior of the barrel by the fluid pressure at the rear of the plunger and closely seal with the interior of the barrel. The wiping element 11 clears the interior surface of the barrel B of loose solid matter so that such solid matter does not pass the sealing flanges 28 or 32 or cut through the sealing flanges to permit the passage of fluid pressure around the plunger. The sealing element 11 thus provides for the efficient operation of the sealing parts 25 and 26 and protects the sealing parts against excessive wear by loose solid matter, etc.

In the event that the core C is relatively loose in the barrel B the workman or operator may insert a pipe or rod in the barrel for the purpose of driving or forcing the plunger through the barrel to remove the core. When this is done the pipe or rod contacts the interior of the metal body 10 or the end 33 of the nut 31 and cannot damage the sealing parts 25 and 26 of the plunger. When the sealing parts 25 and 26 and the wiping element 11 become worn they may be easily and quickly replaced. The plunger is inexpensive and is particularly effective in operation.

Having described only a typical preferred form and application of my invention I do not wish to be limited or restricted to the specific form and application herein set forth, but wish to reserve to myself any modifications or variations that may appear to those skilled in the art or fall within the scope of the following claims.

Having described my invention, I claim:

1. A plunger for forcing a core from a barrel including a hollow body for movement through the barrel and having its rear end open whereby its internal surface is engageable by an implement for forcing the plunger through the barrel, a reduced extension on the front end of the body, a reduced extension on the rear end of the body, an element of resilient material on the front extension for scraping solid matter from the wall of the barrel, a sealing part on the rear extension for cooperating with the wall of the barrel, and means for protecting the sealing part against engagement by the implement.

2. A plunger for forcing a core of earth formation from a barrel including a hollow substantially rigid body having a closed front and an open rear end, the body being adapted for movement through the barrel by an implement pressed

against its open rear end, a projection on the front of the plunger, an element of resilient material on the projection for scraping solid matter from the wall of the barrel, a sealing cup on the projection for cooperating with the wall of the barrel, a reduced extension on the rear end of the body, a sealing cup on the extension for cooperating with the wall of the barrel, and a nut extending into the last mentioned cup and threaded on the extension to retain the last named cup thereon, the nut projecting rearwardly beyond the last named cup to protect the same against engagement by said implement.

3. A plunger for forcing a core from a barrel including a hollow body having a closed front end and an open rear end whereby its interior is engageable by an implement for forcing it through the barrel, a reduced portion at the

forward end of the body providing a forwardly facing shoulder, a reduced portion at the rear end of the body providing a rearwardly facing shoulder, a sealing cup bearing on the first named shoulder and projecting rearwardly therefrom to seal with the barrel, a member threaded on the first named portion and clamping the sealing cup against the shoulder, a sealing cup bearing against the second named shoulder and projecting rearwardly therefrom to seal with the barrel, 10 a nut extending into the second named sealing cup and threaded onto said second named portion to clamp the second named sealing cup against the second named shoulder, and a part on the nut projecting rearwardly beyond the second named sealing cup to protect it against engagement by said implement.

JOHN H. HOWARD.
